CHRISTMAS TREE ORNAMENT

Dario Moranduzzo, Via Aretina 161, Florence, Italy

Filed Oct. 22, 1965, Ser. No. 87,818

Term of patent 3½ years

(Cl. D29—1)

FIG. 2

FIG. 1 is a perspective view of a Christmas tree ornament showing my new design, the other side presenting substantially the same appearance, and

FIG. 2 is a sectional view taken on the line 2—2 of FIGURE 1 to show the contours of the neck, body, and mane.

I claim:

The ornamental design for a Christmas tree ornament, as shown and described.
